UNITED STATES PATENT OFFICE.

WILFRID JACQUES, OF WOONSOCKET, RHODE ISLAND.

RING-HOLDING DEVICE.

1,135,807.

Specification of Letters Patent. Patented Apr. 13, 1915.

Application filed November 12, 1914. Serial No. 871,786.

To all whom it may concern:

Be it known that I, WILFRID JACQUES, citizen of the United States, residing at Woonsocket, in the county of Providence and 5 State of Rhode Island, have invented new and useful Improvements in Ring-Holding Devices, of which the following is a specification.

My present invention pertains to tools; 10 and it contemplates the provision of a simple, compact and easily operated tool through the medium of which the packing rings of a piston may be conveniently held in a contracted state during the putting of 15 the piston in its complementary cylinder, with a view to facilitating such operation.

The invention in all of its details will be 20 fully understood from the following description and claims when the same are read 25 in connection with the drawings, accompanying and forming part of this specification, in which:

Figure 1 is a top plan view showing my 25 novel tool as arranged in proper relation to a piston cylinder, the view being a broken one. Fig. 2 is a broken side elevation of the same. Fig. 3 is a detail section, taken in the plane indicated by the line 3—3 of 30 Fig. 1 and showing the grooves in the slide for receiving the end portions of the metallic strap. Fig. 4 is a detail transverse section illustrating of the manner in which one end portion of the strap is secured detachably in the slide.

Similar numerals of reference designate 35 corresponding parts in all of the views of the drawings.

Among other elements my novel tool comprises a body 1, preferably of rectangular 40 form in cross-section, and preferably, though not necessarily, provided at its under side with a series of beveled teeth 2. On the rear end of the body 1 is an enlargement 3 designed to bear against the palm of the 45 operator's hand, and at the forward end of the body is a flattened portion 4. In the longitudinal center of said flattened portion is a channel 5, designed for the longitudinal passage of the end portions 6 of the metallic 50 strap 7; the forward ends of the side walls of said channel 5 being rounded as indicated by 8 with a view to preventing unnecessary wear of the metallic strap. Pivoted on the flattened portion 4 is a keeper 9, equipped 55 with a finger piece 10, the said keeper in the position shown in Fig. 1 being designed to

retain the strap portions in the channel, and being adapted to be swung to one side of the channel so as to permit of the ready upward movement of the strap portions out 60 of the channel.

Held against turning on and movable lengthwise of the body 1 is a slide 11 having lateral finger pieces 12. The said slide 11 is preferably equipped with a pawl 13, designed to coöperate with the teeth 2 and prevent casual forward movement of the slide when the implement is in use. The pawl 13, however, is not essential to the successful use of my tool, and therefore, like the teeth 2, it 65 may be omitted without involving departure from the scope of my claimed invention. In its upper side the slide 11 is provided with channels 14 and 15 to receive the end parts of the strap 7. The end of the strap in channel 14 is permanently secured by a screw 16, Fig. 2. The end portion in the channel 15 is removable, and therefore with a view to holding said end portion against casual end- 70 wise movement, I provide an enlargement 17 75 on the end portion, which enlargement is removably seated in a socket 18 that communicates with the channel 15. It will also be noticed that the end portion of the strap that is placed in the channel 15 extends rear- 80 wardly beyond the slide 11, by virtue of which said end portion may be readily lifted 85 out of engagement with the slide.

At diametrically opposite or other suitable points on the strap 7 I arrange, by preference, enlargements 20. These enlargements 20 serve when the device is used in the placing of a piston in a cylinder having a flared mouth, to prevent the strap 7 from passing 90 into the cylinder.

In the practical use of my novel tool, the strap 7 is placed about one of the packing rings 21 of a piston 22, either before or after the free end of the strap is arranged and detachably secured in the channel 15 of slide 100 11, as conditions demand. The operator then places his hand on the tool in such manner that the enlargement 3 bears against the palm of his hand while his fingers embrace the lateral projections 12 of the slide 11. 105 The operator then draws the slide 11 toward the enlargement 3 and by so doing contracts the packing ring 21, and in that way assures the said ring entering the piston cylinder incidental to the insertion of the 110 piston.

It will be manifest from the foregoing

that without involving departure from the scope of my claims various changes in the form and proportions of the parts of the tool may be made.

5 Having described my invention, what I claim and desire to secure by Letters-Patent, is:

10 1. A tool for the purpose described, comprising a body having a longitudinally-disposed channel in its forward portion, a slide movable on said body in the direction of the length thereof, and a flexible strap having longitudinally-disposed portions arranged and movable in said channel of the body and 15 also having end portions connected to and movable with the slide.

20 2. A tool for the purpose described, comprising a body having a longitudinal forward channel, a slide movable lengthwise of the body and on the same, said slide having a channel and a socket in communication with the channel, and a flexible strap having longitudinal portions arranged and movable in the channel of the body, and also

25 having one of its ends connected to the slide and its other end removably arranged in the channel of the slide and provided with an enlargement disposed in the socket of the slide.

30 3. A tool for the purpose described, comprising a body having a longitudinal channel in its forward portion, the forward corners of which channel are rounded, an enlargement on the rear portion of the body, a keeper pivoted on the body and movable 35 to and from a position above the channel, a slide movable on the body and lengthwise thereof and having lateral finger pieces, and a flexible strap having portions disposed in said channel, and connected at its ends with 40 the slide.

In testimony whereof I have hereunto set my hand in presence of two subscribing witnesses.

WILFRID JACQUES.
